[57] CLAIM

The ornamental design for a document feeder or the like, substantially as shown and described.

DESCRIPTION

FIG. 1 is a top front and left side perspective view of a document feeder or the like showing my new design;
 FIG. 2 is a top plan view thereof on an enlarged scale;
 FIG. 3 is a front elevational view;
 FIG. 4 is a left side elevational view; and
 FIG. 5 is a right side elevational view.

The undisclosed bottom and rear of the design are substantially plain and unornamented.
